UNITED STATES PATENT OFFICE

WILHELM SCHEPPMANN, OF BERLIN-NEUTEMPELHOF, GERMANY, ASSIGNOR TO C. LORENZ AKTIENGESELLSCHAFT, OF BERLIN-TEMPELHOF, GERMANY

DEVICE FOR TRANSMITTING PICTURES TELEGRAPHICALLY

Application filed February 7, 1929, Serial No. 338,068, and in Germany February 15, 1928.

In systems adapted for the transmission of pictures it is customary to place the light-sensitive cell in the grid circuit of the input tube of an amplifying device and to modulate an alternate current introduced in the way of the said boosting device. Only in this way it is possible to easily further amplify the rather wide band of frequencies of the variations of current produced by the scanning of the picture. In order to avoid the introduction of an alternate frequency it was suggested to apply to the light-sensitive cell a ray of light of varying intensity. For that purpose a rotating perforated disc is usually placed in the path of the light between a source of light and the light-sensitive cell, in order to interrupt the ray of light periodically. In this manner a current of varying energy is obtained in the photoelectric cell, which current can be intensified in known manner by means of any suitable amplifying device. In carrying out this method difficulties will be caused due to the use of the said perforated disc. In order to obtain a sufficiently high number of interruptions of the ray of light per second, it is necessary to employ perforated discs of large size. Through this vibrations of the picture transmitting apparatus are unavoidable. According to the present invention these drawbacks are obviated in that the ray of light is acting periodically upon the light sensitive cell through a control device as for instance, a string galvanometer, an oscillograph or the like.

A mode of execution of the picture transmitting device according to the invention is shown by way of example diagrammatically on the drawing.

The picture drum B is driven by a motor M by the intermediary of a gear wheel Z mounted on the shaft A of said picture drum. A high frequency dynamo is coupled with the driving motor and designated HF. The high frequency currents (ranging between 4000 and 6000 cycles per second) are fed to the thread of the string galvanometer light valve G. The ray of light coming from the source of light L passing through the optical device O₁ is concentrated upon the light con-

trol device G. On the drawing a known string galvanometer is shown as such is customary in the transmission of pictures. The ray of light after passing through the slot of the galvanometer is concentrated by means of the optical lens O₂ upon the picture drum and the reflected light is passed through the optical device lens O₃ to the light sensitive cell S, included in the grid circuit of the input tube R of an amplifier. A suitable biasing voltage is applied to the light-sensitive cell by the battery B₂ while the batteries B₁ and B₃ respectively represent the heating and anode batteries for the tube R.

Through the transformer U connected to the anode circuit of the tube the currents are passed to an additional amplifier not illustrated. As the galvanometer string will oscillate with the frequency of the current generated in the high frequency machine, a periodically interrupted current, which can be efficiently amplified, is flowing through the anode circuit of the tube R.

A further advantage of the arrangement consists in that with a fluctuating number of revolutions of the driving motor of the picture transmission device, the number of cycles of the high frequency generator will fluctuate in the same proportion and in consequence the number of openings of the light control apparatus will remain the same for each point of the picture.

I claim:

In a picture transmitter, a picture to be transmitted, a source of light, a motor, means controlled by said motor for impinging light from said source on successive points of said picture to scan said picture, a galvanometer, a string light valve placed in the path of the light from said source to said picture, a source of alternating currents controlled by said motor and electrically connected to said galvanometer for oscillating said galvanometer at a predetermined frequency, having a definite relation with said speed of scanning, whereby said light is correspondingly varied at the predetermined frequency.

In testimony whereof I have affixed my signature.

WILHELM SCHEPPMANN. 100
